(57) **CLAIM**

The ornamental design for a modular flight deck simulator, as shown and described.

DESCRIPTION

FIG. 1 is a perspective view of a modular flight deck simulator showing my new design;

FIG. 2 is a front view thereof;

FIG. 3 is a back view thereof;

FIG. 4 is right side view thereof;

FIG. 5 is a left side view thereof; and,

FIG. 6 is a top side view thereof.

The broken lines indicate disclaimed portions and form no part of the claimed design.

1 Claim, 4 Drawing Sheets
